CLAIM

The ornamental design for an architectural separation baffle
as shown and described.

DESCRIPTION

FIG. 1 is a perspective view of a first embodiment of an
architectural separation baffle;

FIG. 2 is a top view thereof;

FIG. 3 is a bottom view thereof;

FIG. 4 is a front elevation view thereof;

FIG. 5 is a rear elevation view thereof;

FIG. 6 is a right side elevation view thereof; and

FIG. 7 is a left side elevation view thereof.

FIG. 8 is a perspective view of a second embodiment of an
architectural separation baffle;

FIG. 9 is a top view thereof;

FIG. 10 is a bottom view thereof;

FIG. 11 is a front elevation view thereof;

FIG. 12 is a rear elevation view thereof;

FIG. 13 is a right side elevation view thereof; and

FIG. 14 is a left side elevation view thereof.

FIG. 15 is a perspective view of a third embodiment of an
architectural separation baffle;

FIG. 16 is a top view thereof;

FIG. 17 is a bottom view thereof;

FIG. 18 is a front elevation view thereof;

FIG. 19 is a rear elevation view thereof;

FIG. 20 is a right side elevation view thereof; and

FIG. 21 is a left side elevation view thereof.

FIG. 22 is a perspective view of a fourth embodiment of an
architectural separation baffle;

FIG. 23 is a top view thereof;

FIG. 24 is a bottom view thereof;

FIG. 25 is a front elevation view thereof;

FIG. 26 is a rear elevation view thereof;

FIG. 27 is a right side elevation view thereof; and

FIG. 28 is a left side elevation view thereof.

The drawings include break lines, and any portion of the
architectural separation baffle between the break lines forms

no part of the claimed design. The broken lines in the

(Continued)

drawings depict portions of the architectural separation baffle that form no part of the claimed design.
